TERMINAL STRUCTURE

Howard E. Rhodes, Floral Park, N. Y., assignor
to Aerovox Corporation, Brooklyn, N. Y., a
corporation of New York

Application January 21, 1935, Serial No. 2,655

14 Claims. (Cl. 175—315)

My present invention is concerned with electric condensers, primarily with condensers of the electrolytic type, and has its preferred application in electric motor starting.

5 An object of the invention is to provide a simple, inexpensive and durable arrangement by which only aluminum metal parts are exposed at the interior of the casing for prevention of corrosion, while the mechanical advantages of 10 steel or brass for the exposed binding post connections are yet availed of.

Another object is to provide a construction of the above type, which involves a minimum number of parts, of low cost, and affords a durable 15 waterproof construction, easily installed.

Another object is to afford a neat, compact and convenient binding post panel for an electrolytic condenser, which affords facilities not only for connecting the condensers in circuit, but also for 20 connecting up auxiliary equipment, distinct therefrom, such as the centrifugal switch in electric motor starters.

In the accompanying drawing, in which are shown one or more of various possible embodiments of the several features of the invention,

25 Fig. 1 is a plan view with the cover partly broken away of a condenser, incorporating the invention,

Fig. 2 is an end elevation of the condenser, showing a plan of the panel board,

30 Fig. 3 is a view in transverse section, on an enlarged scale, taken on line 3—3 of Fig. 1,

Fig. 4 is a similar view taken on line 4—4 of Fig. 1,

Fig. 5 is a view similar to Fig. 1, of an alternative embodiment, and

35 Fig. 6 is a transverse sectional view on an enlarged scale, taken on line 6—6 of Fig. 5.

Referring now to the drawing, there is illustratively shown an electrolytic condenser including a conventional condenser roll C made up of formed aluminum foil electrodes 10 and 11, with intervening absorbent sheets 12, carrying electrolyte and with protruding terminal tabs 13 and 14 integral with the respective electrodes. The 40 unit is preferably flattened and, as usual, mounted in a rectangular aluminum container 15, with the usual flat cover 16, crimped thereabout and shown partly broken away.

The panel board preferably comprises a molded 45 block or plate 17 of "bakelite", vulcanite or the like, having integrally molded therewith, end ledges 18 and 19 rising therefrom. The respective ledges have rising therefrom binding posts 20 and 21, preferably of steel or brass, said posts 50 each having a head 22 embedded in the panel

unit and molded thereto. A sheet metal connector strip 23 preferably encircles said post, extends the length of the ledge and is clamped in place by a binding post nut 24 about post 20. The panel at each end has a bushing portion 25 5 at the lower face thereof, lodged in a corresponding aperture 26 in the casing wall. The panel is mounted in place, preferably by means of aluminum studs 27 extending through the casing wall, the panel, the ledge 18 and the connector strip 23, 10 over which the end of said aluminum stud is headed as at 28. Preferably, the stud 27 has a head 29 engaging an aluminum washer 30 pressed against an insulating washer 31 which encircles the bushing 25. A tip 32 on the stud head 29 extends 15 through terminal tab 13, which is clamped against head 29 by upsetting at 33 over an aluminum washer 34. Thus, the aluminum studs 27 in the respective ledges 18 and 19 serve the dual function of affixing the terminal panel 17 to the casing 15 20 and of establishing electrical connection between terminal tabs 13 and 14 of the contained condenser unit and the respective binding posts 20 and 21.

It is preferred, as shown, to dispose the binding 25 posts 20 and 21 at the ends of one diagonal of the panel, and the aluminum studs 27 at the ends of the other diagonal of the panel, which affords a particularly neat and attractive arrangement.

By the arrangement described, the circuit 30 from the condenser to the binding post is from the aluminum stud 27 through the connector strip 23 to the steel or brass terminal binding post 20. Thus, the mechanical strength of steel or brass is availed of, for binding post connection, for which purpose, aluminum is not so practical, while aluminum and no other metal subject to corrosion, is exposed at the interior of the casing. The construction is mechanically 35 secure and waterproof.

Bosses 36 and 37 are shown in Figs. 1, 2 and 4 with steel or brass binding posts 38 and 39 respectively, headed at 40 molded thereto exactly as in the case of binding post 20. Binding posts 38 and 39 which are electrically apart 45 from the condenser C, serve for circuit connection of the centrifugal starting switch (not shown) in electric motor applications or for other apparatus associated with the condenser.

By the arrangement shown, while the panel 50 is quite small, a maximum distance is afforded between each exposed metal part and the casing, and by the staggered or diagonal arrangement of parts, a maximum distance is afforded be- 55

tween consecutive binding post nuts, for a minimum area of panel.

It is, of course, understood that the construction set forth, lends itself for application to a greater or lesser number of binding posts, and that in the case of a grounded condenser unit, with only a single terminal, the ledge 18 alone at one end of the panel might be used for that purpose and the rest of the panel dispensed with.

It is also understood that while, in general, motor starting condensers are disposed in rectangular cases, as shown, the device lends itself for application to cylindrical or other shapes of condenser casings, in which case, the panel board would be molded with appropriate concavity for engagement therewith.

In the construction set forth, the assembly of the parts is particularly easy, the active condenser roll unit may have its terminal tabs 13 and 14 fixed in the first instance, to the aluminum studs 27 before insertion into the casing. After washers 31 and 30 have been slipped over studs 27, these are passed through the apertures 26 as the condenser is introduced into the casing. The panel is then positioned over studs 27 and the ends 28 are upset, which completes the assembly.

In the embodiment of Figs. 5 and 6, the aluminum stud at the interior and the steel or brass stud binding post at the exterior are shown in direct axial alignment, instead of being offset as in Figs. 1 to 4. The aluminum stud element 41 protrudes through the casing wall 15' and at 43 is headed over an aluminum washer 44 which clamps the terminal tab 13' against aluminum washer 45 pressed against insulating washer 46, which in turn engages the inner face of the condenser casing 15'.

Referring to Fig. 6, the brass or steel binding post 47 has a head 48 lodged within a cupped head 49 of the aluminum stud 41, said head staked inward at 50 to pre-assemble said parts. The composite binding post assembly is molded 45 within the insulating block or panel 51 to bond said elements into a unitary rigid construction extending in part into the boss 52. The aluminum stud 41 thus protrudes from one face of the panel and the binding post 47 from the boss 52 at the opposite face thereof.

While the invention has its preferred application to electrolytic condensers of the dry type, particularly for motor starting, it is understood that the invention affords a water tight connection useful also in applications to wet electrolytic condensers.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent of the United States is:—

1. An electrolytic condenser including an active capacity unit, a container can therefor, a

molded insulating panel engaging said can and having a ledge unitary therewith protruding from the exposed face thereof, an aluminum terminal stud through said can and through said panel and ledge, serving to affix said panel to said can, and for terminal connection of said condenser unit, and a metal terminal post molded in said ledge, free from the contents of said can, and means effecting an electrical connection from said aluminum stud to said terminal post.

2. An electrolytic condenser comprising a metal can, a capacity unit within said can, an insulating panel at the exterior of said can, means firmly positioning said panel in contact with the exterior of said can, aluminum studs through said can, electrically connected to the contained condenser, terminal posts molded in said panel at the exterior of said can and means at the exterior of said can associated with said panel, electrically connecting the aluminum studs to the corresponding terminal posts.

3. An electrolytic motor condenser, comprising an aluminum can, an active condenser unit including aluminum foil within the can, a molded insulating panel contacting said can and having integral ledges rising therefrom, aluminum studs extending through said panel and the ledges thereof into said can, and electrically and mechanically bonded to the unit, said studs serving also to affix the panel to the can, terminal posts molded in said ledges, and metal bridge pieces along said ledges electrically connecting the aluminum studs to the respective terminal posts.

4. An electrolytic condenser comprising an aluminum can, an active unit therein including aluminum foil, a molded insulating panel having a face contacting said can and having integral ledges rising therefrom, terminal studs through the can and through the panel at corresponding ledges thereof, said studs electrically engaging the terminals of the unit at their inner ends, and headed over the exposed faces of the ledges for mechanical connection of the panel and electrical connection of the unit, said ledges having terminal posts molded therein, and conducting metal strips on said ledges, electrically connecting the aluminum studs to the respective terminal posts.

5. An electrolytic condenser comprising an active unit having aluminum electrodes, a container therefor, a terminal unit at the exterior of said container, comprising a molded block having a threaded binding post therein, and protruding therefrom, a conducting plate resting on said block and extending therealong from said post, an aluminum stud extending through said container, through said block and through said plate, said stud engaging an electrode of the contained condenser unit for terminal connection thereof and engaging said plate for electrical connection therefrom to the binding post.

6. An electrolytic condenser comprising an active unit including aluminum electrodes with terminal tabs, a rectangular aluminum enclosure can therefor, an insulating molded panel engaging one side of said can and having unitary ledges rising from opposite ends thereof, threaded binding posts molded in and rising from said ledges, conducting metal strips extending along said ledges and connected to said respective posts and aluminum studs extending through the enclosure can and the panel at the respective ledges thereof, headed over said plates at their outer ends, and secured with respect to the condenser tabs at their inner ends.

7. An electrolytic motor starting condenser,

comprising an active unit with aluminum foil electrodes, an aluminum containing can therefor, a molded insulating panel block against one side of said can and having unitary ledges and unitary bosses rising therefrom, each of said ledges and bosses having a binding post molded therein, said ledges, each having a metal connector strip extending therealong, connected to the corresponding binding post, headed aluminum studs extending through the can, and through the respective ledges and the corresponding connector strips and headed thereover, to serve for electrical connection of the contained unit, and for mechanically affixing said panel in place, the binding posts in said bosses serving for electrical connection of apparatus associated with but distinct from said condenser.

8. An electrolytic condenser including an active unit, an enclosure therefor, an insulating terminal-carrying block attached to the exterior of said enclosure, said block having an aluminum terminal stud associated therewith and extending through the wall of said enclosure, for terminal connection to the active unit, said block having a binding post exposed therefrom and electrically connected to said aluminum stud.

9. In an electrolytic condenser, the combination of an active unit, a metal casing therefor, a molded insulating block, an aluminum stud protruding from one face of said block, a binding post protruding from the other face of said block, said stud and post electrically connected at the exterior of said molded block.

10. As an article of manufacture, a binding post panel for an electrical condenser, said panel comprising a molded block having a conductor strip thereagainst, a binding post molded in said block and contacting said strip, said block having a bore therethrough and through said strip adapted to accommodate an aluminum stud, to serve for affixing said block to an electrolytic condenser casing and for electrical connection from a terminal of a condenser to the binding post.

11. As an article of manufacture, a binding

post panel for an electrical condenser, comprising a molded insulating plate having upstanding ledges at its ends and upstanding bosses between said ledges, binding posts molded in said ledges and in said bosses and protruding therefrom, conductor strips extending from the corresponding posts along said ledges, said panel with its ledges being bored in direction parallel to said posts, to accommodate aluminum studs to serve for mounting the panel on a condenser casing, and for establishing electrical connection from the contained unit, to the binding posts on said ledges.

12. In an electrolytic condenser, the combination of an active unit, a metal casing therefor, a molded insulating block, an aluminum stud protruding from one face of said block, a binding post protruding from the other face of said block, said stud and post elements in mechanical and electrical contact at their engaging ends, said insulated block molded about the contacting portions of said stud and said post.

13. In an electrolytic condenser, the combination of an aluminum casing, an active unit therein, having an aluminum electrode with a terminal tab, an insulating block against said casing, said block having a composite binding post structure molded therein, and including an aluminum stud through the lower face thereof, extending into the casing for electrical and mechanical co-action with the terminal tab and a binding post protruding from the exposed face of said block.

14. As an article of manufacture, a terminal block for an electrolytic condenser, said block of molded insulating material, a composite binding post element molded therein, said composite element including an aluminum stud for a non-aluminum post aligned therewith and protruding from opposite faces of said block, both of said elements being headed, one with a cup head for accommodating and embracing the other, said heads maintained in secure electrical contact within the molded block.

HOWARD E. RHODES.
